ELI L. NICHOLS AND F. A. EDLER, OF FOLSOM, CALIFORNIA.

Design No. 3,995, dated April 26, 1870.

DESIGN FOR PRUNING-SHEARS.

The Schedule referred to in these Letters Patent and making part of the same.

To all whom it may concern.

Be it known that we, ELI L. NICHOLS and F. A. EDLER, of Folsom, county of Sacramento, State of California, have invented a new and improved Design for Shears, intended to be used for pruning and grasping purposes; and we do hereby declare that the following is a full, clear, and exact description of the design which we desire to protect, reference being had to the accompanying drawings.

Our design relates to the various portions of that class of pruning-shears which, after severing limb, branch, or twig, grasps it between a suitably-constructed spring and one of the jaws of the shears, and holds it until it is released by the separation of the jaws, and is employed not only for pruning purposes, but also to pick or gather fruits.

The blade or cutting-jaw A of the shears is made in an oval form, having one edge sharpened in the usual manner. The opposite or closing-jaw B has the same amount of curve as the cutting-edge of the blade A, the two vibrating portions of the shears being united in such a manner that, in closing them, a gap or opening of uniform width will result at every point between the two. The effect of this will be that the branch or twig will be cut square off, without being forced by a shear motion toward the points.

In order to construct the shears so as to produce this motion properly, a peculiar formation of the shoulders of the two parts of the shears is necessary. The bolt *a* upon which they move is therefore placed to one side of the center of motion, as shown in the drawings, thus allowing the pressing-jaw to close squarely upon the knife.

In order to prevent any vibration of the two parts,

a curved slot, *e*, is made in the part which carries the cutting-jaw A, and a bolt, *e'*, passes through the slot, being secured in the opposite part, the enlarged head preventing any side movement. The bolt which unites the two parts has simply a square head and nut, instead of the rivet usually employed.

The spring D, which serves for grasping the severed twig or branch, is made in the form of a C, being doubled back upon itself, as shown. This spring is secured to the blade A near the back, and its sweep brings it around to the proper position, near the cutting-point, for grasping whatever may be cut by the knife.

The operating-handles F G are formed in one of the ordinary styles; but the springs *i i*, which serve to keep them separate instead of locking in the usual manner, merely press upon one, another one of them sliding over and past the other in opening and closing the shears, to facilitate which their ends are curved in opposite directions.

The ends of handles are provided with an ordinary spring-catch, *f*, to keep them closed when not in use.

Having thus described our invention,

What we claim, and desire to secure by Letters Patent, is—

The above-described pattern or design for pruning and grasping-shears.

In witness whereof we have hereunto set our hands and seals.
